INVENTOR

Arthur P. Steward

UNITED STATES PATENT OFFICE.

ARTHUR P. STEWARD, OF WASHINGTON, DISTRICT OF COLUMBIA.

PORTABLE STOVE AND OVEN.

SPECIFICATION forming part of Letters Patent No. 329,783, dated November 3, 1885.

Application filed April 29, 1885. Serial No. 163,827. (No model.)

To all whom it may concern:

Be it known that I, ARTHUR P. STEWARD, a citizen of the United States, residing in the city of Washington, District of Columbia, 5 have invented a new and useful Improvement in Portable Combined Stoves and Ovens, of which the following is a specification.

My invention relates to improvements in portable combined stoves and ovens, and is 10 designed for use in direct connection with an ordinary cooking-stove, or independently of said cooking-stove, in connection with either the chimney or the stove-pipe of said cooking-stove in the usual way, or out of doors as a 15 camp-stove.

My invention consists in certain features hereinafter described, and pointed out in the claims.

Figure 1 is a vertical central section of the 20 portable combined stove and oven. Fig. 2 is a view of the portable combined stove and oven in perspective. Fig. 3 is a view in perspective of the double damper.

A is the portable combined stove and oven 25 provided with the draft-opening m and the pot-holes f and g.

The heating chamber or oven E is provided 30 with double walls c and d on four sides thereof, which walls form the flue-space b. Said flue-space has two escape-openings, h and j, and is deepened or enlarged at a point above 35 the oven to form the combustion-chamber a. The two escape-openings h and j are to permit the stove to be used either in connection with an ordinary cooking-stove or independently 40 of said stove. In the flue-space b at the opening h there is a double damper, C, consisting of two plates, k and l, connected by a portion of the handle n. The plate k is of 45 slightly greater height than the flue-space beneath the oven, extends transversely across said flue-space from side to side, and is at right angles to the other plate, l, which is of sufficient size to cover the opening h. Said double damper slides on the bottom of the lower flue-space, and when its handle is pushed in until 50 the upper edge of the plate k strikes against the inner upright wall of that portion of the flue-space b which is between the opening h and the exit j, the said flue-space is closed by said plate, while at the same time the plate l is moved out of coincidence with the opening

h, and thus permits the products of combustion to pass through said opening on either side of that part of the handle n which connects 55 said plates; or, if said double damper be pulled out until the plate k shall be in contact with the outer upright wall of that portion of the flue-space which is between the opening h and the exit j, there will be an unobstructed passage 60 through the entire flue-space from the combustion-chamber a to the exit j, while at the same time the plate l will coincide with the opening h and said opening will then be closed. 65

When it is desired to use the portable stove in connection with the ordinary cooking-stove, the said portable stove is placed thereon, and the opening h made to coincide with one of its pot-holes. The air to support combustion 70 enters through the draft-opening m, and the products of combustion escape through the flue-space b into the ordinary cooking-stove by means of the escape-opening h and the pot-hole i of said cooking-stove. At this time the 75 double damper C is pushed in until its plate k closes that portion of the flue-space between the opening h and the exit j when the plate l is out of coincidence with the opening h, and the products of combustion, being prevented 80 by the plate k from continuing their course from the combustion-chamber a around the oven, escape through the opening h and the pot-hole i of the cooking-stove into the stove; but when it is desired to use the portable 85 stove independently of the ordinary cooking-stove the damper C is pulled out until its plate k comes in contact with the outer upright wall of that portion of the flue-space which is between the opening h and the exit j, when there 90 will be an unobstructed passage through the entire length of the flue-space, and the opening h being closed by the plate l of the damper C, the products of combustion will pass from the combustion-chamber a through the flue- 95 space b around the heating-chamber and escape through the exit j, by means of a pipe, into the chimney or stove-pipe of the cooking-stove, if used indoors, or into the open air if used outdoors. 100

Having thus fully described my invention, what I claim as my invention, and desire to secure by Letters Patent, is—

1. A portable stove which consists of an

oven having double walls which form a flue-space around the same, said flue-space being enlarged or deepened at a point above the oven to form a combustion-chamber, and provided with an escape-orifice through the lower outer wall of the said oven, substantially as described.

2. A portable stove which consists of an oven having double walls which form a flue-space around the same, said flue-space being enlarged or deepened at a point above the oven to form a combustion-chamber, and provided with one escape-orifice through the lower outer wall of the said oven, and with another at the end thereof farthest from the

combustion-chamber, substantially as described.

3. The combination of the oven E, having the surrounding flues b and the escape-openings h and j, with the damper C, located in the flue b below the oven, and having the plates k and l, for preventing the escape of the products of combustion through either of said openings, as desired, substantially as described.

ARTHUR P. STEWARD.
